PHONOGRAPH

Orville M. Dunning, Glen Ridge, N. J., assignor
to Thomas A. Edison, Incorporated, West
Orange, N. J., a corporation of New Jersey

Application October 26, 1940, Serial No. 362,990

8 Claims. (Cl. 274—12)

This invention relates to phonographs and more particularly to commercial phonographs of the disk-record type.

In the more common or conventional arrangement of the disk-record type of phonographic machine the record is rotated at constant angular speed and the engaging stylus of the translating means is moved across the record towards the center thereof at constant linear speed. The engaging stylus will under these conditions form or follow (depending upon whether the machine is operated for recording or reproducing purposes) a spiral groove on the record face, but the linear speed of this groove past the stylus will gradually diminish as the stylus moves through succeeding groove convolutions towards the center of the record. This continuously varying groove speed produces a continuous variation in the recording and reproducing conditions between the translating means and the record, and introduces limitations in the quality which can be attained in the recording and reproducing operations. Also, since the minimum groove speed which may be utilized at the central portion of the record is necessarily limited by the standard or quality to be realized over this portion of the record, and since the speed of the groove at the outer portion of the record is much faster than is necessary to attain this standard, it follows that in this conventional type of machine the playing time of the record is unnecessarily greatly reduced.

To overcome the abovementioned limitations, disk-record type phonographs have been constructed to operate at a constant linear groove speed. This is achieved by progressively increasing the angular or rotational speed of the record, and concurrently effecting a relative translational movement between the translating means and the rotating record, along a stationary radial line of the latter, at a rate proportional to the record rotational speed. The varying rotational speed of the record has been effected by a frictional drive wherein a rotating drive wheel, which is held axially stationary in relation to the translating means, frictionally engages a disk connected to the record support and is fed radially thereacross. The relative translational movement between the rotating record and the translating means may be effected by holding either the record or the translating means stationary and moving the other in translation relative thereto.

The present invention is concerned with a "constant linear groove speed" type of phonograph wherein the record is rotated by way of a

frictional drive of the general form just mentioned and wherein the rotating record is moved in translation, or fed, with respect to a stationary translating means; and it is a broad object of my invention to provide a generally improved form of such a phonograph and to simplify and facilitate its operation and control.

It is another object of my invention to provide new and improved protective means to safeguard the phonograph from misoperation, and particularly in this respect to enforce a correct sequence in the manipulations of separate controls of the phonograph.

Another object of my invention is to provide novel and improved means to facilitate the mounting and removal of a record in relation to the machine. To this end it is a feature of my invention to provide a guideway for directing a record, which is to be mounted, to a substantially central position in relation to the record-support spindle and to provide readily manipulatable means by which the record may then be finally centered and retained in position on its support.

More particularly, it is an object of my invention to provide a record support structure of low-inertia moment so as for example to reduce slippage in the friction drive when the clutch for the drive is engaged to start record rotation. To this end the usual heavy turntable is eliminated and the record is rotatably supported only at its hub portion, there being however provided a stationary table directly below the translating means which serves to slidably support the portion of the record engaged by the stylus. It will be seen that while the elimination of the usual turntable necessitates the use of a drive disk for the frictional record drive above mentioned, this drive disk does not add materially to the moment of inertia of the record-support structure since in accordance with my invention it is made of a light construction.

Another object is to provide a simplified clutch construction for the frictional drive of the phonograph. As a feature of my invention in this respect, the drive disk is very simply mounted—it being directly and rigidly connected at its hub to the record-support spindle—and is moved into and out of frictional engagement with the drive wheel merely by flexing it longitudinally of the spindle.

Other and allied objects and features of my invention lie in the various combinations of elements hereinafter described and will more fully appear from the following description and the appended claims.

In the description of my invention, reference is had to the accompanying drawings, of which:

Figure 1 is a top plan view of a phonograph constructed in accordance with my invention, the top cabinet cover being removed and some cabinet portions being broken away for the better illustration of the interior parts of the phonograph mechanism;

Figure 2 is a vertical sectional view taken substantially along the line 2—2 of Figure 1;

Figure 3 is a left hand elevational view of the record-support carriage and of the parts carried thereby, some stationary parts of the machine appearing however in section along the line 3—3 of Figure 1;

Figure 4 is a fractional rearward view of the record-support carriage just mentioned;

Figure 5 is a vertical sectional view taken substantially along the line 5—5 of Figure 2;

Figure 5a is a fractional front elevational view, at reduced scale, of the phonograph;

Figure 5b is a right-hand elevational view of the structure of Figure 5a;

Figure 6 is a vertical sectional view taken substantially along the line 6—6 of Figure 2;

Figure 7 is a fractional view of the friction drive for the record support illustrating in particular the clutch for the drive;

Figure 8 is a top plan view of a portion of the structure of Figure 7; and

Figure 9 is a vertical sectional view taken substantially along the line 9—9 of Figure 3.

Reference being had to Figures 1 and 2, in particular, there will be seen a top plate 1 of a frame 2 for the phonograph mechanism, which is carried by a lower rectangularly shaped cabinet portion 3 at the level of the top thereof, the plate being hinged to this cabinet portion along its rearward edge as at 4 and supported by this cabinet portion at its front in a manner hereinafter described. The frame 2, which may be a casting, is provided beneath the top plate 1 with left and right standards 5 and 6 and with a short intermediate standard 7 (see Figure 5). The left standard 5 extends from front to back along the width of the top plate and has a rearward portion terminating at its bottom in a horizontal face 5' and a forward portion projecting below the face 5' and of a substantially V shape; the intermediate standard 7 is positioned in the rearward half of the frame and terminates in a lower face 7' which lies in the horizontal plane of the face 5' just mentioned; and the right standard 6 is of the same shape as that of the forward portion of the left standard 5 and is positioned laterally in line with this portion.

Secured by screws 8 to the faces 5' and 7' is a flat plate 9 from which a motor M is resiliently suspended as on posts 10 through compression springs 11 in the manner such for example as is described in Langley Patent No. 2,020,119, issued November 5, 1935, and entitled "Motor supporting means." Carried by the left and right standards 5 and 6 in the forward half of the machine are front and back (and respectively upper and lower) laterally extending rods 12 and 13 on which a carriage 14 for the record-support structure is slidably mounted. The rod 13 is held stationary to the frame 2 by a set screw 15 in the standard 5; the rod 12 is, however, journaled in the standards 5 and 6—for reasons which will hereinafter be apparent—and held longitudinally stationary by a screw 16 in the standard 5 which engages an annular groove 17 in the rod.

The carriage 14, which may also be a casting,

comprises a top horizontal portion 14a having left and right legs 14b and 14c depending therefrom, as shown in Figures 3, 5 and 6. The carriage is mounted on the front support rod 12 by way of a sleeve 20 embracing the rod, the sleeve being secured to the carriage by means of screws 21 passing through a flanged head 20' on one end of the sleeve and threading into a side wall of the carriage. The right leg 14c of the carriage is slotted as at 22 to fit the carriage support rod 13 and to slide directly thereon. The left leg 14b of the carriage is slotted as at 23 in the manner of the leg 14c; this slot is however enlarged to receive a sleeve 24 which embraces the support rod 13. The sleeve 24 extends to the left of the carriage through substantially half the length of the machine and is threaded exteriorly along its outer end portion 24a; this sleeve—which is adapted to serve as a feed screw for the carriage—is mounted for rotation about the support rod 13 and for sliding movement therealong, and is held stationary against translational movement along the support rod in relation to the carriage by a stop collar 25 on the sleeve at the left side of the leg 14b and by the hub of a bevel gear 26 at the right side of the leg, the collar and gear being secured to the sleeve by set screws 27 and 28. Movement of the carriage on the support rods 12 and 13 in a rightward direction is limited by a stop collar 29 on the rod 13 which is securable thereto at any desired point by a set screw 30.

Journaled in the upper carriage portion 14a intermediate the legs 14b and 14c is a vertical spindle 35 serving as a record-support shaft (see Figure 6). Secured to the upper portion of this spindle by a pin 36 is a sleeve 37 having upper and lower flanged ends 37a and 37b. The upper flanged end 37a serves as a rotatable support or turntable for a disk record, this support being however in size equal substantially only to that of the central inactive hub portion of the record. The lower flanged end 37b is riveted at its underside to an annular ring 38. Clamped between this flanged end and ring is a thin drive disk 39 which forms a part of the frictional drive as is hereinafter explained. Between the ring 38 and the upper carriage portion 14a there are interposed ball bearings 40, which are guided in an annular recess 41 provided in a raised boss 41' on the carriage, to form a thrust bearing for the spindle 35. Secured to the lower end of the spindle 35 between the carriage legs 14b and 14c is a pinion 42 which is in mesh with the bevel gear 26 to couple the feed sleeve 24 to the spindle 35. This rotation of the sleeve with the spindle is employed to feed the record supporting carriage 14 in translation along the rods 12 and 13 at a rate proportional to the rotational speed of the record, as is hereinafter explained.

The record support 37a projects slightly above the top plate 1 through an opening 43 therein, which opening extends laterally of the machine so that the top plate will clear the record support in the travel of the carriage. The mounting of a record on the record support 37a is accomplished by sliding the record laterally across the top plate 1 from the right end of the machine into a position wherein the record is centrally located in relation to the spindle 35. To facilitate such placement of the record disk there is provided a guide plate 44 in parallel relation to the top plate 1 and at a small distance thereabove. This plate, which has front

and back turned-down edges 44' of which the latter have ears 45 secured by screws 46 to the top plate 1 to hold the guide plate in position, forms with the top plate 1 a shallow guideway 47 extending laterally of the machine across the record support 37a (see Figure 6). The guideway has at its right end a mouth 47' by way of which it is adapted to receive a disk record and to guide the same into a substantially correctly mounted position in relation to the record support 37a. Although the support 37a projects into the guideway, it does not interfere with the passage of a record therethrough because of a bevel 46 provided on its edge. In order that a record disk may be easily inserted into the guideway, the mouth 47' of the guideway is flared outwardly by curving the guide plate 44 slightly upwardly and the top plate 1 slightly downwardly at the right end of the machine, as at 44'' and 1' respectively.

To stop the movement of a record through the guideway when the record reaches a substantially correct mounting position there is provided a stop member 50 which is bracketed on the left side of the carriage 14, as shown in Figures 1, 3 and 5. This member comprises a horizontally disposed forked portion below the top plate 1 which terminates into a plurality of stop fingers 51. These fingers are circularly arranged about the axis of the spindle 35 and extended upwardly through laterally extending openings 52 in the top plate 1 to a level slightly above the guideway 47. To effect a maximum useful length of the guideway 47, the guide plate 44 is extended beyond the path defined by the stop fingers 51 in the travel of the carriage, the guide plate being, however, arranged to clear the stop fingers by the provision therein along its left-end portion of a notch 53 for each stop finger, as shown in Figure 1.

When a record has been mounted on the support 37a and positioned approximately centrally in relation to the spindle 35 by the record guiding and locating means above described, it is then finely centered and clamped or pressed down firmly against the support 37a by a centering and clamping device in the form of a pivoted arm structure 60 (see Figures 1, 3, 4, 5 and 6). This arm structure comprises an arm 61 carried by the carriage 14 in a position radially overlying a mounted record. The means by which the arm 61 is supported by the carriage comprises a plate 62 secured at its forward end to the carriage 14 by screws 63 and having a pair of turned-up lugs 64 at its rearward end which project up above the top plate 1 through a laterally extending opening 65 in the top plate. Carried by these lugs at their upper end portion is a rod 66 on which the rearward end of the arm 61 is pivoted. The forward end of the arm 61 terminates in a portion 67 substantially in the shape of an inverted cup. Journalled within this cup portion 67 is a short spindle 68 which is received loosely at its upper end by a recess 69, as shown in Figure 6. In this recess, between the end thereof and the end of the spindle, there is provided a ball 70 which forms a thrust bearing for the spindle. The bottom of the cup portion 67 is closed and a loose journal is formed for the spindle by a flanged nut 71 threaded on the cup portion 67. Pinned to the spindle 68 within the cup portion 67 is a stop collar 73 which serves by its abutment against the nut 71 to keep the spindle from falling out of the cup portion 67. Below

the cup portion 67 on the spindle 68 there is provided a disk 74 of substantially the same diameter as that of the record support 37a, and projecting below this disk is a lower end portion 68' of the spindle terminating in a cone 68''. When the arm 61 is swung downwardly into a substantially horizontal position, the lower spindle portion 68' enters the central bore of the sleeve 37 and the disk 74 seats on the record support 37a, the spindle portion and disk each passing through a top opening 75 in the guide plate 44.

The arm 61 is biased downwardly, by a torsion spring 76 at the hub of the arm on the pivot rod 66, and is automatically latched against downward movement when it is swung upwardly into a raised position. The latching means for the arm comprises a detent 77 mounted, by way of pin and slot connections 78, to slide on the arm 61 longitudinally thereof, as shown in Figure 1. This detent is biased rearwardly by a tension spring 79 connected between the detent and the arm. Along the path of the carriage 14 behind the arm 61 there is mounted on the top plate 1 a bracket 80 provided with an overhanging portion forming a catch 81. As the arm 61 is swung upwardly the end 77' of the detent 77 first impinges against the catch 81, to move the detent forwardly, and thereafter the end 77' is slid downwardly over the edge of the catch. When the end 77' of the detent clears the catch 81 it is snapped rearwardly under the catch by the spring 79 to latch the arm 61. To unlatch the arm 61 the detent is manually moved along the arm 61 so as to free the end 77' of the detent from the catch 81. To facilitate such manipulation of the detent, and a manipulation of the arm 61 into upper and lower positions, the detent and arm are respectively provided with fingerpieces 84 and 85.

It will be seen that with the use of the record mounting means above described the mounting of a record on the machine is rendered very simple. For instance, the operator need first only to insert the record in the guideway 47 and to move it therethrough until it impinges against the stop fingers 51, and then to unlatch the arm 61 so that it may swing downwardly in response to its biasing into a lower or operative position. As the record is moved through the guideway against the stop fingers 51 it is brought into a substantially central position in relation to the record-support spindle 35 as heretofore mentioned, and as the arm 61 is next swung downwardly into operative position the cone-shaped end portion 68' of the spindle 68 first enters the central hole in the record to finely center the record and then the disk 74 bears down against the hub portion of the record to hold the record firmly against displacement in relation to the record support. It will also be seen, aside from the record holding or clamping function of the arm structure 60, that when the arm 61 is in its operative position the lower end portion 68' of the spindle 68 obstructs the path of a record through the guideway and thus serves to prevent both the placing of a record into mounted position in relation to the record support and the removal of an already mounted record from the support. Such preventive function is utilized in connection with apparatus hereinafter described to safeguard the machine against certain possible misoperations.

The drive mechanism by way of which the motor M and the record support 37a are cou-

pled together comprises a drive shaft 90 journaled in a sleeve bearing 91 extending from left to right beneath the top plate and held at its left end in the standard 5 (see Figures 6 and 7). Pinned to the outer end of the shaft 90 is a pulley 92 which is coupled to the drive pulley 93 of the motor by a belt 94. The belt is kept taut by an idler pulley 95 journaled to a support lever 96 which is pivoted as at 97 to the motor housing, this lever being biased, to cause the idler pulley to bear against the belt, by a tension spring 98 as shown in Figure 2. Pinned to the inner end of the drive shaft 90 is a drive wheel 99 provided with a frictional drive-surface layer which may, for example, be made of rubber. Movement of the disk 39 into and out of frictional engagement with the drive wheel 99 is controlled by a clutch C. This clutch comprises a pressure wheel 100, similar to the wheel 98, which is caused to bear against the disk 39 at a point thereon directly opposite the driving or engaging surface of the drive wheel 99. The support means for the pressure wheel comprises a bracket 101 secured by screws 102 to the underside of the top plate and having left and right legs 103 and 104 depending therefrom (of which the left leg is curved rearwardly and apertured to embrace the sleeve bearing 90 aforementioned and provide an additional support for this bearing, there being provided a set screw 91' for retaining the sleeve bearing to the leg). Journaled in the legs 103 and 104 is a rock shaft 105. On the right end of this rock shaft there is secured an arm 107 on which there is rotatably mounted the pressure wheel 100, and on the left end of the rock shaft there is secured a control lever 109. The pressure wheel 100 is biased to bear against the disk, to clutch the disk to the drive wheel 99, in response to an angular biasing of the rock shaft 105 caused by a tension spring 110 connected between the bracket 101 and lever 109. The pressure wheel may however be moved at will by the control lever 109 away from the disk so as to remove the driving friction from between the disk and drive wheel and thereby unclutch the drive. In order that the disk 39 will wholly free itself of the drive wheel when the pressure wheel is so moved, the disk is made of a thin flexible material and is provided with a slight upwardly directed bias. The use of a thin flexible disk biased in this way simplifies the construction of the drive coupling in that it permits the drive wheel to be mounted in a stationary bearing, and the frictional disk to be mounted in a stationary bearing in relation to the carriage 14, i. e., simply directly clamped to the spindle 35. Also by making the frictional disk of a thin light material and employing merely a hub support for the record, the moment of inertia of the rotating record-support structure is made very small and, as a consequence, the tendency for slippage between the disk and drive wheel at the moment of starting record rotation is greatly reduced.

The construction of the friction drive hereinabove described is not claimed herein, since such construction forms the subject matter of my co-pending application Serial No. 420,621, filed November 27, 1941, as a division of the present application and entitled "Phonographs."

The means to feed the carriage 14 along the support rods 12 and 13 in response to rotation of the record support spindle 35 comprises the aforescribed feed sleeve 24 and a feed nut 112 which cooperates therewith, as shown in Figures 75

1, 2, 5 and 6. This feed nut is carried by a front-to-back extending rock lever 113 on an arm 114 thereof which extends rightwardly from the rearward end of the lever. The rock lever is pivoted at a point centrally thereof, as at 115, to a boss 116 projecting in from the standard 5. An angular biasing of the lever to urge the feed nut 112 into engagement with the sleeve 24 is effected by a tension spring 117 connected between the lever and the standard 5. Movement of the rock lever 113 to disengage the feed nut from the sleeve 24 and thus render the carriage freely manually movable, as into its initial or starting position at the completion of a feeding movement thereof under the action of the sleeve 24, is effected through the medium of a control means hereinafter described.

It will be seen that when the disk 39 is rotated by the drive wheel 99, while the carriage 14 is under the action of the feeding means just described, each revolution of the disk causes an advance in the travel of the carriage by a fixed amount and as a result the drive wheel engages the disk along a constantly pitched spiral line of progressively smaller radius. As the drive wheel engages the disk at smaller radial distances from the center of the disk, the rotational speed of the disk progressively increases and so also does the travelling speed of the carriage; the linear speed of the portion of the disk at its place of engagement with the drive wheel, however, remains constant throughout the traversal of the disk by the drive wheel.

Supported above the top plate 1 at the left end of the guideway 47, for coaction with a mounted record is a recording and reproducing translating means which by way of example is illustrated as comprising separate recording and reproducing units 120 and 121 (see Figures 1, 2, 5 and 6). These two units are carried by a horizontal plate 122 which is mounted on a pair of upright bosses 123 on the top plate 1, the plate 122 being secured to these bosses by screws 124. The plate 122 has rightwardly extending front and back portions 122a and 122b which form bases for the reproducing and recording units respectively. Secured as by welding to the bases 122a and 122b are respective upright posts 125 to which the translating units 121 and 120 are respectively pivotally connected for up and down freedom of movement in relation to a supported record. In the case of the recording unit this pivotal connection is effected by a bail member 126 firmly secured along its body portion to the unit as by welding and pivoted to the post by means of cone pivots 127 which pass through the separate legs of the bail member to engage the post from opposite sides thereof. In the case of the reproducing unit 121, the pivotal connection affording the up and down freedom of movement to the unit is effected in substantially the same manner as that of the recording unit—there being a bail member 128 connected to the unit and pivoted to the post 125 by means of cone pivots 127 which pass through the legs of the bail member into engagement with opposite sides of the post. In this latter case, however, the bail member 128 is not firmly connected to the reproducing unit but is instead pivotally connected thereto about a vertical axis so as to afford also a lateral freedom of movement to the unit, this lateral freedom of movement being necessary to permit the reproducing unit to freely track a spiral groove on a rotating record. The pivotal connection by which this lateral freedom of

movement is provided comprises a pair of ears 129 turned back from the bail member 128 so as to straddle the end of the unit 121, and pivots 130' extending vertically through the ears and engaging the unit at its upper and lower sides.

The recording and reproducing units herein diagrammatically shown may be of any suitable type—for example, of the piezo-electric type—and need not herein be described other than that the units are respectively provided with recording and reproducing styli 131 and 132 at the lower free end portions thereof, as shown in Figure 2. These styli are mounted directly above the drive wheel 99 in order that the record groove in its movement past the styli will partake of the constant linear speed characterizing the movement of the engaged portion of the disk 39 past the drive wheel. As shown in Figure 1, each of the units 120 and 121 are tangentially disposed with respect to the point of contact of their respective styli with the record, by an angular positioning of the posts 125, such disposition serving to stabilize the action of the units in their coaction with a moving record. The portion of the moving record engaged by the styli is supported vertically by a table 134 on which the record is permitted to slide, as shown in Figure 6. This table is mounted on the top plate 1 and is provided with a highly polished top surface in order that the sliding friction between it and the bottom of the record will be greatly reduced.

The recording and reproducing units 120 and 121 are placeable into operative and inoperative conditions in relation to a mounted record merely by lowering and raising the units into and out of a resting position wherein their styli engage the record. This lowering and raising of the units is effected through a slide 138 which is mounted on the plate 122 through pin and slot connections 139 for back and forth movement along the left sides of the translating units. Turned up from the slide along its right side is a vertical cam plate 140 and extending to the left from the translating units 120 and 121 are lift tabs 141 and 142 which directly overlie the top edge of the cam plate 140. This top edge of the cam plate has a raised central dwell 140a terminating in front and back downwardly inclined cam faces 140b and 140c, as shown in Figure 2. When the slide 138 is in its most forward position the tab 141 is free of the dwell 140a to permit the recording unit to engage the record whereas the tab 142 is engaged by the dwell to hold the reproducing unit in a raised or inoperative position; when the slide is in an intermediate position both tabs are engaged by the dwell and both recording and reproducing units are thus held from the record in inoperative position; and when the slide is in its rearward position the tab 141 is engaged by the dwell to hold the recording unit in inoperative position but the tab 142 is now free of the dwell to permit the reproducing unit to engage the record. The tab 142 on the reproducing unit is shaped in the form of an inverted V so that when the tab is engaged by the cam plate 140 to lift the unit from the record the unit will be centered with respect to its lateral freedom of movement.

The selective conditioning of the translating means, the engaging of the carriage feeding means, and the clutching of the drive mechanism are all manually controlled by a control lever 145. This lever, which is carried with the carriage 14, is rotatably mounted on the sleeve 20 between the carriage legs 14b and 14c, and pro-

jects angularly upwardly and forwardly from its hub through a laterally extending opening 146 in the front of the lower cabinet portion as is hereinafter described. The separate elements controlled by the control lever 145 have a common coupling to the lever through the medium of the support rod 12 and it is for this reason that the rod 12 is journalled in the standards 5 and 6 as heretofore mentioned. A coupling of the control lever to the rod 12 is effected by a spline connection formed by a screw 147 which extends through the hub of the lever into slidable engagement with a slot 148 provided in the rod 12 longitudinally thereof. Each of the control functions of the lever 145 are achieved in accordance with the angular positioning of the rod 12. The coupling between the rod 12 and the feed nut 112, to control the engaging of the carriage-feeding means, comprises an upturned finger 113a on the rock lever 113 and a V-shaped cam 149 on the rod 12, which cam is part of a collar 150 secured to the rod at its left end portion (see Figures 2 and 5). Similarly, the coupling between the rod 12 and the pressure wheel 100, to control the clutching of the drive mechanism, comprises a camming surface 151 on the control lever 109 and a V-shaped cam 152 on the rod 12, which cam is part of a collar 153 secured to the rod 12 to the right of the collar 150 (see Figures 2, 5 and 7). The coupling between the rod 12 and the slide 138, to control the conditioning of the translating units, comprises an upright arm 154 secured to the collar 153, a right angle arm 155 extending leftwardly from the slide 138 and then downwardly through an opening 156 in the top plate, and a link 157 interconnecting the arms 154 and 155 and pivotally connected thereto as at 158 and 159 respectively (see Figures 1, 2 and 5).

The operation of the control means of the foregoing paragraph is as follows: When the control lever 145 is in its central or inoperative position—the position occupied by the lever in Figure 3—the cam 149 bears against the top of the finger 113a to hold the feed nut 112 out of engagement with the sleeve 24, the cam 152 engages the camming surface 151 to raise the pressure wheel 100 and thereby render the clutch C disengaged, and the slide 138 is held in its central position to render both the recording and reproducing units inoperative. When the control lever 145 is moved downwardly from its central or inoperative position into a position hereinafter referred to as its recording position—the position occupied by the lever in Figure 2—the cam 149 slides off the back side of the finger 113a and the feed nut is engaged with the sleeve 24 in response to the biasing of the rock lever 113, the cam 152 slides rearwardly off from the camming surface 151 and the clutch C is engaged in response to the biasing of the lever 109, and the slide 138 is moved forwardly to permit the recording unit to move downwardly into engagement with the record in response to its own weight while retaining the reproducing unit in inoperative position. When, instead, the control lever 145 is moved upwardly from its inoperative position into a position hereinafter referred to as its reproducing position, the cam 149 slides off the front side of the finger 113a and the feed nut 112 is again engaged with the sleeve 24, the cam 152 slides forwardly off from the camming surface 151 and the clutch C is again engaged, and the slide 138 is moved rearwardly to permit the reproducing unit to engage the record while yet retaining the recording unit in in-

operative position. When the control lever 145 is returned from either of its operative positions (i. e., its recording or reproducing positions) to inoperative position it will be understood that the reverse actions from those just described will take place.

In the course of an operation of recording dictation it is customary for a dictator to intermittently interrupt the operation of the machine (i. e., temporarily stop the record rotation) to give him time to formulate in his mind the further course of his thoughts. To permit such interruption in the operation of the machine, without disturbing any other of its adjustments, there is provided an independent actuating means for the clutch C which is in the form of a clutch-actuating mechanism 201. This mechanism is herein fractionally shown in Figure 2 as of the construction disclosed in Langley Patent No. 1,380,486, issued June 7, 1921, and entitled "Controlling device," to which patent reference may be had for a description of the mechanism in all its details. For the present it is sufficient to say that this actuating mechanism comprises a pair of stop and start electromagnets 202 and 203 respectively operating the pivoted armatures 204 and 205, which armatures are suitably interconnected so that each, when in unactuated position, is effective to lock the other in its actuated position and so that each, when it is moved into actuated position, will as a terminal result thereof cause the other to be moved into its unactuated position. One of the armatures, say 204, is coupled to the lever 109 by a link 206. This link has at one end a pivotal connection 207 to the armature and has at its other end a lost motion or pin and slot connection 208 to the lever 109, the lost motion connection being provided in order that the lever 109 may be operated to disengage the clutch by the control lever 145, as heretofore described, without incurring any actuation of the mechanism 201. This mechanism is contained in a box 209 and is held by screws 210 to an inward extension 211 on the standard 5.

As appears in the abovementioned Langley patent, when a circuit is established to cause current to flow through the stop electromagnet both armatures are swung in the direction of that electromagnet to disengage the clutch. When the armatures have substantially reached their terminal positions in that movement, a switch is operated to break the circuit of the stop electromagnet and to prepare the circuit of the start electromagnet for energization. When the start electromagnet is next energized, the reverse action takes place, the clutch being engaged, the circuit through the start electromagnet being broken, and the circuit of the stop electromagnet being prepared for energization.

There is provided, as a safeguard to the stylus of the translating means and to the record, a protective means which is adapted to prevent both record mounting and record removal while either translating unit is in an operative or record engageable position, and also to prevent either translating unit from being placed into operative position while the arm 61 is raised to permit a change of record. The first preventive function here mentioned is adapted to safeguard either stylus from being accidentally impinged upon by the record during record mounting, and conversely, the record from being scratched by the stylus during record mounting and record removal; and the second of these preventive functions is adapted to safeguard the stylus from being damaged

through a lowering of the translating units upon the table 134, as at a time when there is no record mounted on the machine.

This protective means is in the form of an interlock mechanism between the control lever 145 and arm 61 and comprises, as shown in Figure 3, a slidably mounted bar 165 controlled in its movement by the lever 145 and a tail piece 166 on the arm 61 which coacts with this bar. The bar 165 extends from front to back below the top plate 1 and has a pivotal connection at its front end, as at 167, to an arm 168 extending rearwardly from the control lever, there being integrally formed with the hub of the control lever 145 a sector-shaped web 169 from which the arm 168 extends, this web being provided for reasons which will hereinafter be explained. The rearward end portion of the bar 165 has a pin and slot connection 170 to the leftward one of the lugs 64 to provide a slideable mounting for the bar. The tail piece 166 projects down from the hub of the arm 61 between the lugs 64 and then extends forwardly beneath the top plate. On the end portion of the tail piece there is provided a cross pin 171 which directly underlies a flat horizontal edge 172 at the bottom of the bar 165. This edge is adapted to obstruct the pin 171 against upward movement and to thereby lock the arm 61 in its lower or operative position. The edge 172 is however interrupted intermediately thereof by an upwardly extending slot 173 in the bar, which is adapted to permit, as when the slot is positioned directly above the pin 171, an upward swinging of the arm 61.

The slot 173 is positioned on the bar 165 to directly overlie the pin 171 when the control lever 145 is in inoperative position. Thus when the control lever is in inoperative position to retain both translating units 120 and 121 in inoperative position the arm 61 may be raised to permit record removal and record remounting. When the arm 61 is so raised the control lever 145 becomes locked in inoperative position through the engagement of the pin 171 with the slot 173, this locking of the control lever being adapted to prevent any accidental lowering of either translating unit on the table 134 when there is no record mounted on the machine. When the arm 61 has however been lowered to operative position, as in the completion of record mounting, and the control lever 145 shifted into recording or reproducing position the bar 165 is moved forwardly, or rearwardly as the case may be, to bring portions of the edge 172 over the pin 171, and to thereby lock the arm 61 in lowered position, this locking of the arm 61 being adapted to prevent record change while either translating unit is in a record engageable position.

The lower cabinet portion 3 heretofore mentioned has its front wall terminating along the top thereof into an inwardly curved arcuate portion 180 (see Figures 1, 2 and 3). This arcuate portion, except for the ends thereof, which are integral with the cabinet portion 3, comprises a removable wall section 181. The wall section 181 is provided with an upturned flange 182 along the top thereof which is secured by screws 183 to the front edge of the top plate (see Figures 2 and 5a), and with a turned back flange 184 along the lower edge thereof which is adapted to seat upon a flange 185 turned back from the top edge of the front wall of the lower cabinet portion (see Figure 2). This wall section 181, it will be seen—forms the means by way of

which the phonograph mechanism is supported at its front by the lower cabinet portion as was heretofore mentioned.

In the wall section 181 there is provided the opening 146 through which the control lever 145 passes. This opening is made relatively long so that the wall section will not obstruct the travelling movement of the carriage 14. The opening is, however, effectively closed by an arcuate shield 186 which is carried by the aforementioned sector-shaped web 169 and by a similarly shaped web 187 that is positioned to the right of the web 169 and integrally formed with the control lever, as shown in Figures 3 and 9. The shield is secured to these webs by means of brackets 188 which are welded to the shield and fastened to the webs by screws 189.

A lefthand portion of the flange 182, which is turned up from the wall section 181 is extended to provide a vertical wall 190, as shown in Figure 5a. On the front face of this wall section there is provided a suitable holder 191 for an index slip, and bracketed to the carriage 14, at 192 as shown in Figures 1 and 3, is an arm 193 extending leftwardly from the carriage and then terminating into an upturned finger 194 which extends through a slit 195 in the wall section 181 to overlie the index slip holder 191. This finger is adapted to serve as a guide for a pencil or the like, by means of which explanatory marks or annotations may be made on the index slip, during the course of a recording operation, as with respect to selected portions of recorded matter.

Over the top of the machine there is provided a cover 196. This cover fits the top edge of the rearward and left side walls of the lower cabinet portion 3 and forms a vertical extension of these side walls of the cabinet, as shown in Figures 2 and 5, there being provided inwardly turned flanges along the left side walls of the cover and lower cabinet portion, as at 197 in Figure 5, to form a good seat for the cover. The front of the cover is partially cut away in its left half portion, at 198, to fit the wall 190, as is shown in Figure 5a. In the right half of the cover at the front, top and right sides thereof, as is shown in Figures 5a and 5b, there is provided an opening 199 which is arranged to expose the record mounting means and the mouth of the record guideway 47. As appears in Figure 5, the top edge of the right wall of the lower cabinet portion is provided with an inwardly turned flange 200; the rearward portion of this flange serves as a seat for the cover whereas the forward portion forms with the curved portion 1' of the top plate an outward extension of the mouth 47' of the record guideway.

Although I have herein shown and described my invention in terms of one embodiment thereof, it will be understood that this embodiment is subject to many changes and modifications without departure from the scope of my invention which I endeavor to express according to the following claims.

I claim:

1. In a phonograph comprising a support onto and from which a record may be mounted and removed, and a translating means adapted to cooperate with a record mounted on said support: the combination of a control means associated with said translating means and movable into operative and inoperative positions to place the translating means into and out of operative

relationship with a mounted record; a rotatably held member movably mounted for movement between an inoperative position and an operative position wherein the member bears against a mounted record to hold the same in mounted position on said support; and an interlock between said control means and said member causing either one to be locked upon the placing of the other into a predetermined one of its positions.

2. In a phonograph comprising a record support and a translating device placeable into operative and inoperative conditions in relation to a record mounted on said support: the combination of a control means associated with said device and movable into operative and inoperative positions to place the device into its respective conditions; a rotatably held member arranged to bear against a mounted record and movably mounted for movement into an ineffective position and into a bearing position wherein the member is effective both to obstruct a mounting of a record on said support and to hold an already mounted record on the support; and an interlock between said control means and said bearing member and effective when the former is in operative position to lock the latter in its said bearing position, and when the latter is out of bearing position to lock the former in operative position.

3. In a phonograph comprising a record support and a translating device placeable into operative and inoperative conditions in relation to a record mounted on said support: the combination of a control means associated with said device and movable into operative and inoperative positions to place the device into its respective conditions; a movably mounted member adapted for independent manipulation into an ineffective position and into an effective position wherein the member is immediately adjacent to a mounted record to prevent any substantial movement of the record from said support; and an interlock between said control means and said member permitting movement of each independently of the other and adapted to lock the control means in inoperative position when the member is in ineffective position and to lock the member in effective position when the control means is in operative position.

4. In a phonograph comprising a support onto and from which a record may be mounted and removed: the combination of a translating device and control means associated therewith movable into operative and inoperative positions to place the device into operative and inoperative conditions in relation to a mounted record; a movably mounted member adapted for independent manipulation into an ineffective position and an effective position wherein the member is adapted to bear against a mounted record to obstruct both the mounting and removal of a record in relation to said support; and an interlock between said member and said control means permitting each to be moved independently of the other and effective to cause either one to be locked upon placing the other into a predetermined one of its positions.

5. In a phonograph comprising a rotatably mounted support onto and from which a record may be mounted and removed: the combination of a translating device and a control member operatively associated therewith and movable to adjust the device into operative and inoperative

conditions in relation to a record mounted on said support; rotatable means; a member movably supporting said rotatable means and biased to cause the rotatable means to bear axially against a mounted record whereby to hold the record on said support; and means, operatively connecting said control member with said supporting member, for causing either member to be locked upon placing the other member into a predetermined one of its positions.

6. In a phonograph including a support onto and from which a record may be mounted and removed and a translating device supported for operative association with the record; the combination of obstructing means to prevent a change of record in relation to said support and adapted to be operated by the hand; a control means operatively associated with said translating device and manipulatable into operative and inoperative positions to place the device into and out of operative relation with the record; and an interlock between said control means and said obstructing means permitting independent manipulation of said obstructing means while said control means is in inoperative position and of said control means only when said obstructing means is in operative position and adapted to lock said obstructing means in operative position when said control means is in operative position and to lock said control means in inoperative position when said obstructing means is in an inoperative position.

7. In a phonograph having a turntable onto and from which a record is to be mounted and removed, and a carriage movably supporting said

turntable for linear travelling movement: the combination of stationary guide means associated with said turntable and forming a narrow guideway across the face of and in line with the direction of travel of the turntable, said guideway being open-ended at one side of the turntable for receiving and guiding a disk record onto the turntable; and means, comprising a stop member fixedly held to said carriage and extending into said guideway at the other side of the turntable, for limiting the passage of a record into said guideway to a substantially central position relative to the turntable irrespective of the position occupied by the turntable in its range of travelling movement.

8. In a phonograph comprising a record support and a translating device placeable into operative and inoperative conditions in relation to a record mounted on said support: the combination of a control means associated with said device and movable into operative and inoperative positions to place the device into its respective conditions; a movably mounted member adapted for independent manipulation into an ineffective position and into an effective position wherein the member is immediately adjacent to a mounted record to prevent any substantial movement of the record from said support; and means intercoupling said control means and said member and permitting movement of either independently of the other for locking the control means in inoperative position when the member is in ineffective position.

ORVILLE M. DUNNING.

CERTIFICATE OF CORRECTION.

Patent No. 2,341,703.

February 15, 1944.

ORVILLE M. DUNNING.

It is hereby certified that error appears in the printed specification of the above numbered patent requiring correction as follows: Page 7, second column, line 29-30, claim 2, for the word "operative" read --inoperative--; and that the said Letters Patent should be read with this correction therein that the same may conform to the record of the case in the Patent Office.

Signed and sealed this 15th day of August, A. D. 1944.

Leslie Frazer

(Seal)

Acting Commissioner of Patents.
